UNITED STATES PATENT OFFICE.

HENRY B. PATCH, OF KANSAS CITY, MISSOURI, ASSIGNOR TO GENESY ELECTRIC LANTERN COMPANY, OF RAWLINS, WYOMING, A CORPORATION OF WYOMING.

FLASH LIGHT.

Application filed September 17, 1925. Serial No. 56,897.

My invention relates to improvements in flash lights. It is particularly adapted for use in connection with flash lights which are portable and have a cylindrical casing from one end of which light is adapted to be projected.

One of the objects of my invention is to provide a flash light of the kind described which is simple, cheap, durable, not liable to get out of order, which is provided with a novel handle which enables it to be conveniently carried and held in different positions in the hand, and which is provided with novel supporting means by which it may be retained for use in an inclined or in a horizontal position.

The novel features of my invention are hereinafter fully described and claimed.

In the accompanying drawing, which illustrates the preferred embodiment of my invention,

Fig. 1 is a side elevation, partly broken away, of a flash light provided with my improvement.

Fig. 2 is a cross section thereof.

Fig. 3 is a side elevation of the same shown in the tilted position.

Fig. 4 is a perspective view of one of the supporting members, and a portion of the transverse connecting member attached thereto.

Fig. 5 is a front view of one of the U-shaped legs.

Similar reference characters designate similar parts in the different views.

1 designates the cylindrical casing of an ordinary flash light of the type which is portable and which has at one end a lens 2 through which light is adapted to be projected from an electric lamp 3 in the casing.

For supporting the flash light in different positions when it is in use and unsupported by the hand, I provide two legs under the casing 1, and disposed one forward of the other, and which comprise each, preferably, a U-shaped resilient wire having a horizontal supporting transverse portion 4 and two arms 5.

Two pairs of supporting members 6, disposed one pair forward of the other, are provided. The members 6 of each pair are fastened, as by rivets 7, to opposite sides respectively of the casing 1 and project below the casing.

Each member 6 is provided with a trans-

verse hole 8, and a lateral projection, preferably an arcuate flange 9, disposed concentric with the hole 8 on the inner side of the member 6, which constitutes abutment locking means, and which at its ends terminates at two notches or recesses 11 located in radii from the hole 8 which are at right angles to each other.

The arms of each leg are respectively extended through and are pivotally mounted in the holes 8 of the members 6 of the adjacent pair, so as to be swung from an upright supporting position, shown in dotted lines in Fig. 1 to a position parallel with the casing 1, as shown in solid lines in Fig. 1.

Each arm 5 is provided with an inwardly extending U-shaped portion 10 through which the adjacent flange 9 is adapted to pass. Each arm 5 is adapted to be sprung into the two recesses 11 at the ends of the flange, whereby the latter releasably holds the arm in either the upright supporting position or in the position parallel with the casing 1.

Two brace transverse members 12 are fastened to and connect the supporting members 6 of the two pairs.

A longitudinal U-shaped handle 13 has its arms fastened to the upper side of the casing. It enables the casing to be conveniently carried and held in different positions with the hand.

When it is desired to use the flash light in a horizontal position, the arms 5 are disposed as shown in dotted lines in Fig. 1, in which position they are releasably held by the flanges 9. If it is desired to have the flash light disposed in use in an upwardly tilted position, the rear leg is swung to the parallel position and the forward leg to the upright position shown in Fig. 3.

When the light is to be carried or stored, both legs may be swung to the parallel position shown in solid lines in Fig. 1. The flanges 9 will hold the legs in such parallel position.

The flash light is well adapted for use in working about an automobile, as the legs enable it to be fixed in different positions adapted for the particular work in hand.

I do not limit my invention to the structure shown and described, as many modifications, within the scope of the appended claims, may be made without departing from the spirit of my invention.

What I claim is:—

In a flash light of the kind described, the combination with a flash light casing, of two pairs of supporting members, the members of each pair being provided each with abutment locking means, and two U-shaped legs the arms of which are respectively pivoted to said supporting members, each of said arms being adapted to be swung to two radial positions and in such positions en-

gaging and being releasably held by said adjacent abutment means, said two pairs of supporting members being disposed one pair forward of the other pair at the under side of said casing, whereby the legs may be positioned to support the flash light casing horizontally, or upwardly or downwardly tilted. 15

In testimony whereof I have signed my name to this specification.

HENRY B. PATCHÉ.
